UNITED STATES PATENT OFFICE.

LOUIS P. WEBERT, OF WATERBURY, CONNECTICUT.

HEATER.

Application filed August 11, 1926. Serial No. 128,637.

The primary intent of this invention is the provision of a device for utilizing the exhaust from an engine for heating. The principle purpose however, is to utilize the 5 exhaust from an internal combustion engine for heating automobiles, busses and motor vehicles generally propelled by a motive plant including an internal combustion engine.

10 The invention furthermore contemplates the ventilation of the vehicle by supplying fresh warm air thereto at a pressure slightly in excess of atmosphere pressure and to so construct the heater that there is no likelihood of the warm air being contaminated 15 by the admixture therewith of any exhaust gases that may escape at the joints.

15 The invention also supplies a device which is efficient for heating and ventilating, compact in structure, adapted to be readily assembled, or taken apart, and which may be conveniently attached to the vehicle in any advantageous position.

20 While the drawings illustrate a preferred embodiment of the invention, it is to be understood that in adapting the means to meet specific needs and requirements, the design may be varied and such other changes in the minor details of construction may be 25 resorted to within the scope of the invention as claimed, without departing from the spirit thereof.

25 For a full understanding of the invention and the merits thereof, reference is to be had to the following description and the drawings hereto attached, in which,

30 Figure 1 is a horizontal sectional view of a heater embodying the invention, and

35 Figure 2 is a detail sectional view on the line 2—2 of Figure 1, looking to the left as designated by the arrows.

40 Corresponding and like parts are referred to in the following description and designated in both views of the drawings by like reference characters.

45 The heater comprises a rectangular casing through which the air to be heated is circulated and caused to travel in a tortuous path, said casing having an inlet 1 and an 50 outlet 2, preferably disposed at diagonally opposite points. The casing is preferably formed of plates which are connected in any determinate way to admit of the parts being readily assembled or taken apart as required.

55 Tie rods 3 connect opposite plates of the casing in which are preferably formed the

inlet and the outlet openings to which are fitted collars for attachment of the pipes not shown, whereby the air to be heated is supplied to the casing and the warm air discharged from the casing is delivered to the interior of the vehicle or other place to be heated. The plates 4 forming opposite side walls of the casing are clamped between the plates 5 which are connected by means of the tie rods 3 and are connected to plates 6 by means of angle irons 7 which may be attached to the respective plates in any determinate way. The walls 4 and 5 are suitably lined with asbestos or other refractory material, as indicated at 8, to prevent material loss of heat. The casing may be of any capacity and may be attached to the vehicle preferably exteriorly thereof in any determinate way, and for convenience, the plates 6 are extended to provide for receiving the fastenings or other attaching means. A plurality of pipes 9 extend across the space 10 of the casing and project through openings formed in the plates 6 and obtain a close fit with said plates to practically prevent the passage of air. Plates 11 are spaced from the respective plate 6, and are connected thereto. Openings are formed in the plates 11 opposite the ends of the pipes 9 and flanged collars 12 are fitted in said openings and receive the ends of the pipes 9, as shown most clearly in Figure 2. One of the plates 11 is rigidly connected to the adjacent plates 6 whereas the companion plate 11 is yieldably connected to the adjacent plate 6 at the opposite side of the casing. In this manner provision is had for contraction and expansion of the pipes 9 incident to the cooling and the heating of the device. The 70 rigid connections are indicated at 13 and the yieldable connections at 14. These connections consist of bolts passing through openings formed in the plates 6 and 11 and spacing sleeves mounted upon the bolts and arranged between the plates to hold them apart the required distance. Open coil springs 15 are mounted from the bolts constituting the yieldable connections 14. The 75 number of the pipes 9 between the walls 5 will depend upon the capacity of the heater and this is true of the number of pipes provided between the walls 4. Similar boxes 16 are located at diagonally opposite points of the casing and are bolted or otherwise secured to the respective plates 11 and each 80 has an opening and a collar in line with the

opening. One of these collars, as 17, corresponds to the inlet for the exhaust, and the other collar corresponds to the outlet for the exhaust as indicated at 18. Other boxes 19 are bolted or otherwise secured to the respective plates 11 and the exhaust travels therethrough. The box 16 having the inlet 17 connects with one end of the first of the pipes 9 and the opposite end 10 of said pipe or pipes connects with the opposite box 19 with which one end of the second pipe, or pipes, connects. The opposite end of the second pipe, or pipes, connects with the box 19 at the same side of 15 the casing as the box 16 having the inlet 17, and this box is in turn, connected with one end of the third pipe, or pipes 9. In this manner the exhaust passes through the pipes 9 and boxes 19 in successive order and 20 finally discharges through the outlet 18 from which it may be conveyed to the required point of discharge into the atmosphere. The exhaust, in its travel through the pipes 9 heats the space 10 and warms the air cir- 25 culating through said space. Baffles 20 and 21 in the length of the space 10 and projecting from opposite plates 6 compel the air in its passage through the casing to travel in a tortuous path. These baffles may be secured in place in any preferred way. Covers 22 enclose the boxes 16 and 19 at 30 opposite sides of the casing and may be of any construction and attached to the respective plates 11 in any determinate way. These covers are hollow and protect the boxes and the spaces are filled with asbestos 35 22^a or other refractory material to prevent loss of heat. The collars of the boxes 16 corresponding to the inlet 17 and the outlet 40 18 project through the openings formed in the respective covers 22, thereby admitting of coupling of the pipes thereto, whereby the exhaust from the engine is supplied to the heater and conveyed therefrom after circu- 45 lating through the series of pipes 9 and the boxes connected therewith.

In accordance with the invention the air to be heated is filtered, if need be, and is supplied to the casing under pressure. The 50 warm air from the casing is discharged through the outlet 2 and may be conveyed to the interior of the vehicle in any preferred

way by means of a pipe, not shown, fitted to the outlet 2. The pure warm air being supplied to the vehicle under pressure in excess 55 of the atmospheric pressure causes a discharge of the air from said vehicle thereby insuring ventilation as well as heating. The air pressure within the casing being greater than the pressure of the atmosphere there 60 is no tendency of the air passing through the heater being contaminated even though any of the exhaust gases should escape at the joint of the pipes 9 with any of the boxes. It is also observed that the pipes 9 65 pass beyond the walls of the casing and are jointed to the boxes a distance therefrom, hence should any of the exhaust escape it will readily pass off and not enter the cas- 70 ing and contaminate the air passing therethrough for subsequent use in heating and ventilating in the manner stated.

Having thus described the invention, I claim:

1. A heater comprising a casing having 75 an inlet and an outlet, plates at opposite sides of the casing and spaced therefrom, one of the plates being rigidly connected to the casing and the other plate being yieldably connected to the casing, a plurality of 80 pipes extending through the casing and the walls thereof to which the said plates are connected and coupled to the latter, and boxes carried by said plates and connecting the ends of the pipes to provide a passage 85 for the circulation of exhaust through the said pipes for heating the air passing through the casing.

2. A heater comprising a casing having 90 an air inlet and an air outlet, plates at oppo- 95 site sides of the casing and spaced therefrom, means rigidly connecting one of the plates to the casing, means yieldably connecting the other plate to the casing, pipes extending through the casing and the walls 100 thereof to which the said plates are connected and having their projecting ends coupled to the said plates, boxes mounted upon the plates and connecting the ends of the pipes and covers carried by the plates and enclos- 105 ing the boxes mounted thereon.

In testimony whereof I affix my signature.

LOUIS P. WEBERT. [L. S.]
